Primary Examiner—Cathron C. Brooks*Assistant Examiner*—Rosemary K. Tarcza*(74) Attorney, Agent, or Firm*—Alfred N. Goodman; Mark S. Bicks; Jenae C. Avallone(57) **CLAIM**

The ornamental design for a power outlet plug, as shown and described.

DESCRIPTION

FIG. 1 is a front perspective view of the power outlet plug in accordance with a first embodiment of the present invention;

FIG. 2 is a rear perspective view thereof;

FIG. 3 is a top perspective view thereof;

FIG. 4 is a side perspective view thereof;

FIG. 5 is a front perspective view of the power outlet plug in accordance with a second embodiment of the present invention;

FIG. 6 is a rear perspective view thereof;

FIG. 7 is a top perspective view thereof; and,

FIG. 8 is a side perspective view thereof.

The broken line showing is included for the purpose of illustrating environmental features and forms no part of the claimed design.
